UNITED STATES PATENT OFFICE.

EDWIN J. SAMSON AND LOUIS LEVI, OF NEW YORK, N. Y.

SHAVING-BRUSH.

SPECIFICATION forming part of Letters Patent No. 662,973, dated December 4, 1900.

Application filed March 16, 1900. Serial No. 8,992. (No model.)

To all whom it may concern:

Be it known that we, EDWIN J. SAMSON and LOUIS LEVI, citizens of the United States, and residents of the city of New York, borough of 5 Manhattan, county and State of New York, have invented a certain new and useful Shaving-Brush, of which the following is a specification.

Our invention relates to shaving-brushes; 10 and its object is to combine with such a brush means for containing a supply of powdered soap and for regulating the feeding of the powdered soap to the bristles of the brush as occasion may require.

15 By means of the invention the necessity for a mug to contain the soap is dispensed with, and in a single compact article there are provided the brush, soap, and receptacle for holding the latter.

20 Our shaving-brush will be found particularly serviceable to traveling men, as it may be readily carried in the pocket and is always in readiness for use. It may be inclosed in a case with the razor or in a separate case, and 25 it may be made ornamental or plain, and the soap-receptacle and holder for the bristles may be made of various materials.

In the accompanying drawings, Figure 1 is 30 a longitudinal section of a shaving-brush embodying our improvement and showing the parts so adjusted that the soap will not be fed into the supply-tube entering the bristles. Fig. 2 is a similar view showing the parts so adjusted that the soap may be fed to the bristles. Fig. 3 is a cross-section on the line 3 3 of Fig. 1, and Fig. 4 is a similar section on the line 4 4 of Fig. 2.

The same numerals of reference designate 40 the same parts in the several views of the drawings.

Referring to the drawings, 5 indicates the bristles of the brush, which are firmly fixed in the metallic holder 6 by means of a suitable cementing substance 7, and through the 45 latter there is provided an opening, preferably slanting, so that its upper end is to one side of the center of the holder, for the reception of a preferably conically-shaped tube 8, which may be easily removed, so that it may 50 be cleaned out in case there should be any tendency to clog at its lower end. The tube 8 extends just into the bristles, slightly sepa-

rating the bristles, as shown. The upper end of tube 8 when in place is in the space between the cementing substance and the bottom of the coupling or cap which connects the holder 6 to the handle or soap-receptacle, and such upper end is provided, preferably, with a solid offset 9. The feed and the cutting off of the feed of the soap are not, however, dependent upon the use of offset 9.

The receptacle for the soap, which also serves as the handle of the brush, is indicated at 10. It is provided at its top with a cap 11, which is adapted to be removed by means of 65 the screw-threaded connection, as shown. At its bottom the receptacle 10 is provided with interior screw-threads to receive the screw-threaded cap or coupling 12, which is also screw-threaded at its bottom, whereby it is detachably connected to the holder 6. The central part of the coupling 12 is solid, with the exception of a small hole 13, made through it to one side of its center, which is adapted to be brought over the tube 8 to place the 70 soap-receptacle 10 and said tube in communication.

From Fig. 1 it will be seen that the bottom surface of the rim of the coupling 12 is hard down upon the top edge of the holder 6. In 80 this position the hole 13 of the coupling is over the solid offset 9 of the tube 8, and the powdered soap will not pass out of its receptacle into the space beneath. By holding the handle of the brush in one hand and unscrewing with the other hand the holder 6, turning it half-way around, the hole 13 will be brought over the tube 8, thus placing the soap in its receptacle in communication with the feeding-tube extending into the bristles, 85 as seen in Fig. 2. The soap will now flow down tube 8 in a sufficient quantity, and then by turning back the holder 6 to the position seen in Fig. 1 communication between the soap and bristles will be cut off. Stops could 90 be provided on the holder and the coupling to determine the degree of movement necessary to bring the parts in the position shown in Fig. 2; but this is not essential to the satisfactory operation of the device.

Having thus described our invention, what we claim as new, and desire to secure by Letters Patent, is—

1. A shaving-brush comprising a hollow

handle serving as a receptacle for powdered soap, a suitable holder provided with bristles, a feeding-tube extending longitudinally through the holder and entering the bristles, 5 and a coupling adjustably connecting the hollow handle to the bristle-holder, the central portion of said coupling being solid but provided with a hole which, by suitable adjustment of the holder with relation to the handle, can be placed in communication with the feeding-tube to furnish a supply of soap to the bristles.

2. The combination with the bristle-holder, a cementing substance fixing the bristles in 15 the holder and provided with an opening longitudinally through it and a tube arranged in said opening and furnishing a communication between the bristles and the top of the holder, of a hollow handle having a removable cap, and a coupling fixed to the bottom of the handle and provided with a solid central portion with a hole pierced through it, and also provided with a depending screw-threaded portion adapted to screw into the 20 top of the holder.

3. The combination with the hollow handle

having a removable cap and a bottom pierced with a hole through it, to one side of its center, said bottom piece having a depending screw-threaded member, of a bristle-holder 30 provided with bristles, a removable tube extending through said holder into the bristles with its upper end to one side of the longitudinal center of the holder.

4. The combination with the hollow handle 35 provided with a bottom piece pierced with a hole through it, to one side of its center, said bottom piece having a depending screw-threaded member, of a bristle-holder provided with bristles, a tube extending through the 40 holder into the bristles with its upper end to one side of the longitudinal center of the holder and provided with a solid offset.

Signed at New York, borough of Manhattan, county and State of New York, this 3d 45 day of March, 1900.

EDWIN J. SAMSON.
LOUIS LEVI.
